US00D673967S

(12) **United States Design Patent**
Pearcy et al.

(10) **Patent No.:** **US D673,967 S**
(45) **Date of Patent:** **** Jan. 8, 2013**

(54) **COMPUTER HAVING GRAPHICAL USER INTERFACE**

(75) Inventors: **Derek Patton Pearcy**, San Francisco, CA (US); **Jessica J. Gaskins**, Boulder Creek, CA (US)

(73) Assignee: **McAfee, Inc.**, Santa Clara, CA (US)

(**) Term: **14 Years**

(21) Appl. No.: **29/404,936**

(22) Filed: **Oct. 26, 2011**

(51) LOC (9) Cl. **14-04**

(52) U.S. Cl. **D14/486**

(57) **CLAIM**

The ornamental design for a computer having graphical user interface, as shown and described.

DESCRIPTION

FIG. 1 is a perspective front view of a first embodiment of a computer having graphical user interface according to the present design;

FIG. 2 is a front view thereof;

FIG. 3 is a perspective front view of a second embodiment of a computer having graphical user interface according to the present design; and,

FIG. 4 is a front view thereof.

The computer shown in broken lines form no part of the claimed design.
